The ornamental design for a combined pillow with a jewelry roll, as shown and described.

DESCRIPTION

FIG. 1 is a perspective view of an ornamental design for a combined pillow with jewelry roll showing my new design in the unrolled open position;
FIG. 2 is a top plan view thereof;
FIG. 3 is a bottom plan view thereof;
FIG. 4 is a left side elevational view, the right side being a mirror image of that shown;
FIG. 5 is a front elevational view thereof;
FIG. 6 is a rear elevational view thereof;
FIG. 7 is a top plan view of a first modified embodiment of the design shown in FIGS. 1 through 6; and,
FIG. 8 is a top plan view of a second modified embodiment of the design shown in FIGS. 1 through 6.
The cross hatching represents conventional fabric and is understood to extend throughout the areas represented. The broken-lines represent stitching. The sole difference between the three embodiments resides in the appearance of the arrangement of the sections on the top panel.
